[57] CLAIM

The ornamental design for a line marker buoy, as shown and described.

DESCRIPTION

FIG. 1 is a front elevational view of a line marker buoy showing my new design, the rear being a mirror image;
FIG. 2 is a side elevational view thereof, the opposite side being a mirror image;
FIG. 3 is a bottom plan view thereof on a reduced scale;
and
FIG. 4 is a top plan view thereof on a reduced scale.

FIG. 1FIG. 3FIG. 2FIG. 4
